UNITED STATES PATENT OFFICE.

LLOYD RAYMOND STEELE, OF AUBURN, NEW YORK.

DESIGN FOR AN AUTO-RADIATOR CAP.

59,987.

Specification for Design.

Patented Dec. 13, 1921.

Application filed May 6, 1921. Serial No. 467,282. Term of patent 3½ years.

To all whom it may concern:

Be it known that I, LLOYD RAYMOND STEELE, a citizen of the United States, residing at Auburn, Cayuga county, State of New York, have invented a new, original, and ornamental Design for Auto-Radiator Caps, of which the following is a specification, reference being had to the accompanying drawing, forming part thereof.

The Figures 1 and 2 are, respectively, a side view and a front view of an auto radiator cap showing my new design.

I claim:—

The ornamental design for an auto radiator cap as shown.

LLOYD RAYMOND STEELE.
